US00D978276S

(12) **United States Design Patent** (10) **Patent No.:** **US D978,276 S**
(45) **Date of Patent:** **** Feb. 14, 2023**

(54) **LASER TARGET**

(71) Applicant: **Jianmei Wang**, Weinan (CN)

(72) Inventor: **Jianmei Wang**, Weinan (CN)

(73) Assignee: **Jianmei Wang**, Weinan (CN)

(**) Term: **15 Years**

(21) Appl. No.: **29/860,442**

(22) Filed: **Nov. 18, 2022**

(51) **LOC (14) Cl.** 22-04

(52) **U.S. Cl.**

USPC **D22/113; D21/306**

(58) **Field of Classification Search**

USPC D22/113, 114; D21/301, 302, 306, 308

CPC F41J 5/02; F41J 5/24; F41J 1/01

(57) **CLAIM**

The ornamental design for a laser target, as shown and described.

DESCRIPTION

FIG. 1 is a front, top and right-side perspective view of the first embodiment of a laser target, showing my new design; FIG. 2 is a front, top and right-side perspective view thereof in a state of use;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, top and right-side perspective view of the second embodiment of a laser target, showing my new design;

FIG. 10 is a front view thereof;

FIG. 11 is a rear view thereof;

FIG. 12 is a left side view thereof;

FIG. 13 is a right side view thereof;

FIG. 14 is a top view thereof; and,

FIG. 15 is a bottom view thereof.

The broken lines in the drawings illustrate the portions of the laser target, which form no part of the claimed design.

1 Claim, 15 Drawing Sheets
